2 SHEETS—SHEET 2.

UNITED STATES PATENT OFFICE.

LOUIS C. KUEHNER, OF ST. LOUIS, MISSOURI, ASSIGNOR TO HANDLAN-BUCK MANUFACTURING COMPANY, OF ST. LOUIS, MISSOURI, A CORPORATION OF MISSOURI.

ELECTRIC LAMP.

1,416,096.

Specification of Letters Patent. Patented May 16, 1922.

Application filed June 23, 1920. Serial No. 391,172.

To all whom it may concern:

Be it known that I, LOUIS C. KUEHNER, a citizen of the United States of America, a resident of the city of St. Louis, in the 5 State of Missouri, have invented certain new and useful Improvements in Electric Lamps, of which the following is a full, clear, and exact description, reference being had to the accompanying drawings, forming 10 a part of this specification.

My invention relates to electric lamps and it is especially adapted for use in signal lamps in the form of lanterns. The main 15 object of my invention is to provide a support for the lamp bulb which shall be adjustable so that the source of light may be adjusted to and maintained at the focal point of the lens.

My invention provides for the use of any 20 shape or size of bulb or filament and it enables the various different bulbs to be accurately adjusted to the most desirable focal relation to the lens.

Fig. I is an elevation of a signal lamp with 25 parts broken away to show my invention applied.

Fig. II is an enlarged vertical section taken approximately on the line II-II of Fig. I.

30 Fig. III is a plan view of the lamp support as viewed from above.

Fig. IV is a view similar to Fig. I illustrating another form of the invention.

Fig. V is an enlarged top or plan view of 35 the lamp support shown in Fig. IV.

Fig. VI is a vertical section taken through the telescoping supporting members shown in Fig. IV.

Fig. VII is a top or plan view of the elements shown in Fig. VI.

In Figs. I, II and III of the drawings is shown a signal lamp having a shell or casing A, a base B and a hooded cap C. A lens D is secured to the casing A and has the 45 usual guard E. Attached to the inner surface of the casing wall is the adjustable support F, said support comprising a vertical or upright member 1 which is bent at its upper end to form a horizontal supporting arm 2 which extends inwardly from the casing wall. Elongated slots 3 are provided in the upright portion 1, these slots being in vertical alinement and adapted to receive 50 adjustable tightening devices in the form of 55 bolts 4 which pass through the casing wall,

said bolts being threaded at their inner ends to receive nuts 5 by which the upright may be adjustably secured to the casing. Washers 6 may be inserted between the nuts and upright.

Slidable on the laterally bent portion 2 of the upright is a lateral extension member 7, said lateral member 7 carrying the socket 8 at one end and having an elongated slot 9 near its other end, adapted to receive a screw 10 which passes through the slot and into a threaded aperture in the portion 2 of the upright member. A washer 11 may be inserted between the screw 10 and a lateral member 7.

The vertical slots 3 of the upright member provide for vertical adjustment of the socket support, and the slot and screw connection between the member 7 and the horizontal extension 7 of the upright 2 provides for a pivotal movement of the member 7 upon the screw 10 and also for a horizontal adjustment longitudinally of member 7. The member 7 may be moved horizontally relative to the portion 2 a distance equal to 75 the length of the slot 9. The socket 8 is suitably threaded to receive a bulb 12 and is also adapted to receive an electrical conductor 13 which leads to any suitable source of power.

Whenever it is desired to adjust the support in order to place the bulb at the focal point of the lens, the adjusting screws 4 or 10 may be loosened, the lamp support adjusted and the screws then again tightened. 90 A universal adjustment of the lamp is thus secured, which is simple, inexpensive and easily and accurately accomplished.

In Fig. IV, A' designates the shell or casing, B' the base, C' the hood, and D' is 95 a closure for the casing. The lens E' is provided with a guard F'.

The adjustable support shown in Figs. IV to VII comprises a tubular upright member 1' having a flanged foot 2' which may be 100 secured to the base B' in any suitable manner. The base B' has an aperture 3' in alinement with the bore of the tubular upright member 1'. The upright member 1' is split (Figs. VI and VII) preferably at 105 its upper end in order to provide a resilient clamping portion and has attached to it a clamping ring 4' carrying a tightening screw 5'.

Pivottally mounted in the upright 1' and 110

telescoping therewith is another tubular member 6', preferably made of insulating material such as pressed fibre, said tubular member 6' being adapted to pass through the 5 opening 3' in the base B' and is held in position within the member 1' by the clamping ring 4'. To the upper end of the member 6' is attached a pair of horizontally adjustable members 7' and 8', the member 7' including a collar 9' secured to the member 6'. The members 7' and 8' are slidable relative to each other, one of them as for example 8', being provided with an elongated slot 10' and the other member 7' being apertured 10 and threaded to receive tightening screw 11' which passes through the aperture in one member and the slot in the other. The end of the member 8' adjacent the member 6' is forked at 12' so as to embrace the collar 9' 15 and thus be guided in a straight line longitudinally of the slot 10'. The other end of the member 8' is provided with a socket 13' adapted to receive an electric lamp bulb 14'. A conducting cord 15' is attached to the 20 socket 13' and extends through the tubular member 6' and is connected to any suitable 25 source of electrical energy.

Whenever it is desired to adjust the support to accurately locate the bulb at the 30 focal point of the lens, the member 8' may be moved relative to the member 7' by first loosening the screw 11', and if any vertical adjustment is required, the clamping means 4' is released and the tubular member 6' is 35 raised or lowered in the hollow upright 1'. The tubular upright 1' allows of the pivotal adjustment of the member 6' and its attached horizontal members.

From the foregoing it will be understood 40 that bulbs and filaments of different shapes and different sizes can be accurately adjusted to the focal point of the lens. Furthermore, in small bulbs the filaments are not accurately located centrally of the bulbs and

it is therefore desirable to adjust the lamp 45 socket whenever a new bulb is inserted therein, the object being to locate the filament in the most effective position relative to the lens.

I claim:

1. A lamp having a casing, a lens, a lamp socket adapted to receive a bulb, and supporting means for said lamp socket, said supporting means comprising a slotted upright member bent to form a supporting 55 arm at one end, retaining means extending through the slot in said slotted upright member whereby the upright member may be retained in different vertical positions, a lateral extension member having an elongated slot therein, said lamp socket being carried by said lateral extension member, and retaining means extending through said slot in the lateral extension member and through said supporting arm of the upright 60 member whereby the lateral extension member is pivoted to and horizontally adjustable 65 relative to said upright member.

2. A lamp having a casing, a lens, a lamp socket adapted to receive a bulb, and a lamp-supporting device whereby said lamp socket may be adjusted relative to said lens, said lamp-supporting device comprising an upright supporting member adjustable vertically relative to said lens, a supporting arm extending from said upright supporting member, said supporting arm having an extension secured to and supporting said lamp socket, said extension being adjustable in a straight line relative to said arm so as to move said lamp socket toward and away from said lens, said extension being also adjustable horizontally in an arc of a circle, and a screw whereby said extension is secured to said supporting arm.

In testimony that I claim the foregoing I hereunto affix my signature.

LOUIS C. KUEHNER.
